UNITED STATES PATENT OFFICE.

LUTHER C. MCNEAL, OF ROCHESTER, NEW YORK.

CLIP.

SPECIFICATION forming part of Letters Patent No. 727,418, dated May 5, 1903.

Application filed August 4, 1902. Serial No. 118,295. (No model.)

To all whom it may concern:

Be it known that I, LUTHER C. MCNEAL, of Rochester, in the county of Monroe and State of New York, have invented a new and useful Improvement in Clips, of which the following, taken in connection with the accompanying drawings, is a full, clear, and exact description.

My invention relates to clips for use in detachably holding invoices, letters, or other papers, and has for its object the production of a device for the desired purpose which is particularly simple in construction and strong and durable in use; and to this end the invention consists in the combination, construction, and arrangement of the component parts of a clip, as hereinafter fully described, and pointed out in the claims.

Clips heretofore made have been composed of a frame attached to a base-board, a clamping member, and a spring for holding them in operative position. Said clamping member has been usually pivoted midway between its front and rear edges to the stationary member, its rearward extension forming a lever or handpiece. In operating such clips both hands are needed in order to hold the base-board and at the same time press upon the handpiece.

The chief features of my improvement are, first, it occupies less space upon a desk or table, because the usual rearward-extending part of the clamping member is omitted; second, it requires the use of only one hand to operate, as any downward pressure upon the operating member tends to hold the clip more firmly on its support; third, it greatly facilitates the arranging, holding, and releasing of papers, because the clamping member may be locked in its raised position, thus allowing the free use of both hands for such arranging; fourth, it is provided with a hanger by which it may be suspended, and the said hanger may readily be swung out of the way when the clip is used on a desk or table.

Other advantages and purposes of my invention will be more fully pointed out in the following description, in which reference is had to the accompanying drawings, forming part of this specification, in which like letters indicate corresponding parts in all the views.

In the accompanying drawings, Figure 1 is

a plan view of my clip as applied to a base-board or suitable support and showing in dotted lines the position of the operating member when depressed to raise the clamping member. Fig. 2 is a perspective view of the same from the rear with part of the clamp broken away. Fig. 3 is a cross-section on dotted line 3 3, Fig. 1, showing the clip in the open position. Fig. 4 is a cross-section on dotted line 4 4, Fig. 3. Fig. 5 is a perspective view from below of the operating member. Fig. 6 is a top view of a portion of the clamping member C, showing the perforation through which the operating member moves.

My improved clip comprises a stationary member, of any suitable form, and a clamping mechanism for detachably securing papers or other articles to the same.

The parts of my clip may be composed of any suitable material, but are usually stamped, bent, or formed from sheet metal with suitable dies.

The stationary member is usually composed of a base-board A and a sheet-metal frame B, firmly attached thereto, but both these parts may be of sheet metal, integral, if desired. The frame B is preferably constructed as shown in Figs. 1, 2, 3, and embodies a horizontal portion b and a vertical flange b' at its front edge and parts of same b² forming guards for alining papers against. It is provided with the vertical ears b⁴, having perforations b⁵ for supporting the shaft G, and ears b⁷, having perforations b⁸ for supporting the shaft H. At its rear edge are ears or brackets b⁶, which support the pivotal ends e of a hanger E. The front flange b' is provided with downwardly-projecting lugs b⁹ for indenting into the face of the base-board A and preventing papers from slipping under the frame B.

The spring F may be made of any suitable form, but is usually, as shown in Fig. 2, a coiled spring encircling the shaft G, with its central portion f pressing against the ends e of the hanger E on the rear of frame B and its ends f' pressing against the rear portion of the clamping member C. This causes the forward edge of the clamping member to be pressed downward firmly upon the papers or articles placed on the base-board beneath it.

The clamping member C is provided with

ears c , having perforations c' for connecting it pivotally with the ears b^4 of the frame B. It also has a perforation c^2 , through which the operating member D passes, and a downwardly-turned flange c^4 , which forms a bearing-surface, the use of which will be fully explained hereinafter.

The operating member D is a lever, having a handpiece d^3 and the downwardly-projecting ears $d^4 d^5$, and is pivotally attached to the ears b^7 of the frame B by the shaft H through perforations d^3 in the ears $d^4 d^5$. One of the said perforations d^3 is of oblong shape for the purpose of allowing a lateral movement 15 to the handpiece d^3 of the operating member D. It is also provided with a catch d^6 and a lug or cam d .

The hanger E is usually formed of a piece of wire bent into the shape shown in Figs. 1, 20 2, 3. Its end portions e rest in brackets or ears b^6 and are embraced and pivotally held there by the portion f of the spring F. This construction allows a limited rocking movement 25 of the hanger while the pressure of the portion f of spring F holds it in either of its adjusted positions, as shown in full and broken lines, Fig. 3.

The mode of operating my clip is as follows: The clamping member is raised for the 30 insertion or withdrawal of papers or other articles by pressing upon the handpiece d^3 , which causes the lever D to rock on its shaft H and the lug or cam d to press against the bottom of flange c^4 of the clamping member 35 C. This moves the clamping edge to its raised position and frees whatever may be held by it. When the pressure is removed from the handpiece, the spring F causes the clamping member to resume its operative position. When it is desired to lock or latch 40 the clamping member in its raised position for the easy arrangement of letters or papers, it may be readily done by pressing the handpiece d^3 down to its lowest position and 45 moving the same sidewise to the left, as indicated by broken lines in Fig. 1, which causes the catch d^6 to engage the lip c^3 on the clamping member. This side movement of the catch d is permitted by the oblong shape of 50 the perforation d^3 in the ear d^5 . In Fig. 3 the broken lines d^0 and c^0 indicate the paths which are taken by the parts d^6 and c^3 when the handpiece d^3 is moved downward.

The construction and operation of my improved clip will now be readily understood upon reference to the foregoing description and the accompanying drawings.

It will be noted that the exact construction and arrangement of the parts may be more 60 or less varied, as indicated herein, and consequently I do not limit myself to the exact construction and arrangement shown.

I claim as my invention—

1. A paper-clip comprising a stationary 65 member, a clamping member, a supporting-shaft therefor, a spring for holding said clamp-

ing member in operative position, and an operating member consisting of a lever, pivoted in front of the shaft supporting the clamping member and swinging downward and forward 70 for raising said clamping member.

2. A paper-clip comprising a stationary member, a clamping member, a spring for holding said clamping member in operative position, and an operating member; said 75 clamping and operating members being separately pivoted to the stationary member and adapted to swing toward the front of clip, the downward movement of the operating member causing the elevation of said clamping 80 member.

3. A paper-clip comprising a stationary member, a clamping member, a spring for holding the clamping member in operative position and an operating member consisting 85 of a lever pivoted beneath the clamping member and swinging toward the front of clip for raising the clamping member.

4. A paper-clip comprising a stationary member, a clamping member, a spring for holding said clamping member in operative position, and an operating member pivoted to the stationary member, said operating member having a handpiece arranged above the clamping member adapted to swing downward toward the front of clip, for raising said 95 clamping member.

5. A paper-clip comprising a stationary member, a clamping member, a spring for holding said clamping member in operative 100 position, and a pivoted operating member swinging toward the front of clip; said clamping member being provided with a perforation for the passage therethrough of the operating member, said operating member being adapted to raise the clamping member 105 when pressed downward and forward.

6. A paper-clip comprising a stationary member, a clamping member, a spring for holding said clamping member in operative 110 position, an operating member adapted to swing downward toward the front of clip for raising the clamping member, and means for locking said clamping member in its inoperative position.

7. A paper-clip comprising a stationary member, a clamping member, a spring for operating said clamping member, and a hanger held in place on said stationary member by 115 said spring.

8. A paper-clip comprising a stationary member, a clamping member, a shaft for said clamping member; a spring encircling the shaft to which said stationary member and clamping member are pivoted, and a hanger 120 held in place on the stationary member by said spring.

9. A paper-clip comprising a stationary member, a spring-actuated clamping member and a pivoted operating member swinging toward the front of clip, for raising said clamping 125 member; said operating member being

also adapted to move sidewise and provided with a catch for locking said clamping member in its inoperative position.

10. A paper-clip comprising a stationary member; a clamping member movable to and from the stationary member; a spring for pressing said clamping member toward said stationary member; and a separate operating member having a forward movement toward the clamping member for raising the latter.

11. A paper-clip comprising a stationary member; a clamping member movable to and from the stationary member; a spring for pressing said clamping member toward said stationary member; and a separate operating member having a forward movement toward the stationary member for raising the clamping member.

12. A paper-clip comprising a stationary member; a clamping member movable to and from the stationary member; a spring for pressing said clamping member toward said stationary member; a separate operating member having a forward movement toward the clamping member for raising the latter; and means for locking said clamping member in the raised position.

13. A paper-clip comprising a stationary member; a clamping member movable to and from the stationary member; a spring for pressing said clamping member toward said stationary member; a separate operating member having a forward movement toward the stationary member for raising the clamping member; and means for locking said clamping member in the raised position.

14. A paper-clip comprising a stationary member; a clamping member movable to and from the stationary member; a spring for pressing said clamping member toward said stationary member; a separate operating member having a forward movement toward the clamping member for raising the latter; and provided with means for locking said clamping member in the raised position by an additional movement of said operating member.

15. A paper-clip comprising a stationary member; a clamping member movable to and from the stationary member; a spring for

pressing said clamping member toward said stationary member; a separate operating member having a forward movement toward the stationary member for raising the clamping member, and provided with means for locking said clamping member in the raised position by an additional movement of said operating member. 55

16. A paper-clip comprising a stationary member; a clamping member movable to and 60 from the stationary member; a spring for pressing said clamping member toward said stationary member; a separate operating member having a forward movement toward the clamping member for raising the latter; 65 and means for engaging said operating and said clamping members for locking the clamping member in the raised position.

17. A paper-clip comprising a stationary member; a clamping member movable to and 70 from the stationary member; a spring for pressing said clamping member toward said stationary member; a separate operating member having a forward movement toward the stationary member for raising the clamping 75 member; and means for engaging said operating and said clamping members for locking the clamping member in the raised position.

18. A paper-clip comprising a stationary 80 member; a clamping member; a spring for holding said clamping member in the clamping position; and an operating member consisting of a lever pivoted independently of the clamping member and swinging toward 85 said clamping member for raising the latter.

19. A paper-clip comprising a stationary member; a clamping member pivoted to said stationary member; a spring for holding said clamping member in clamping position; a 90 separate operating member movable toward the clamping member for raising the latter, having a catch for engaging said clamping member and retaining the latter in the raised position.
